UNITED STATES PATENT OFFICE

134,295

DESIGN FOR A COMBINED COSMETIC SHELF AND TRAY

Margaret Roscow Steward, Butte, Mont.

Application February 3, 1942, Serial No. 105,617

Term of patent 7 years

To all whom it may concern:

Be it known that I, Margaret R. Steward, a citizen of the United States, residing at Butte, in the county of Silver Bow and State of Montana, have invented a new, original, and ornamental Design for a Combined Cosmetic Shelf and Tray, of which the following is a specification, reference being had to the accompanying drawing, forming part thereof.

Figure 1 is a perspective view of a combined cosmetic shelf and tray showing my new design, and

I claim:

The ornamental design for a combined cosmetic shelf and tray, as shown.

MARGARET ROSCOW STEWARD.
